A. DOWNES

FASTENING FOR BRACELETS, NECKLACES, AND OTHER ARTICLES OF JEWELRY

Filed Dec. 28, 1926

Patented May 10, 1927.

1,628,494

UNITED STATES PATENT OFFICE.

ANDREW DOWNES, OF LONDON, ENGLAND, ASSIGNOR TO CARTIER LIMITED, OF LONDON, ENGLAND, A BRITISH COMPANY.

FASTENING FOR BRACELETS, NECKLACES, AND OTHER ARTICLES OF JEWELRY.

Application filed December 28, 1926, Serial No. 157,554, and in Great Britain January 19, 1926.

This invention relates to fastenings such as are employed for bracelets, necklaces, and other articles of jewelry wherein two members (e. g. the opposite ends of a bracelet or like article) require to be detachably secured together; the object of the invention being to provide an improved construction of snap-fastening having an additional or safety lock.

10 The improved device of the present invention comprises a slotted striking-plate on the one member, having at its rear side a sliding catch which tends under spring action to move in the direction to close the slot; a hasp on the other member adapted to pass through the slot in the striking-plate and preferably having a cam-surface for causing the sliding catch to move automatically in the direction to open the slot 15 during the passage therethrough of the hasp, which latter is adapted for interlocking engagement with the sliding catch to prevent mutual separation of the members after such passage has taken place; a 20 plunger for enabling the sliding catch to be at will moved in the direction to open the slot and release the hasp; and a tumbler-lever adapted so to engage the plunger as to prevent actuation thereof. The tumbler-lever, which preferably is pivoted to the second or hasp-member, may be adapted so to engage the plunger on the first or striking-plate member as to assist in preventing separation of the members from one another 25 after the fastening has been closed. Two or more hasps with a corresponding number of slots in the striking-plate may be employed, the necessary catches being provided on a single spring-actuated slide adapted for 30 operation by one plunger.

In the drawings,

Figure 1 is a plan view partly in section of a fastening embodying the invention, such fastening being shown in the closed or fastened position, and

Figure 2 is an elevation of the same,

Figure 3 is a plan view showing the parts separated,

Figure 4 is an elevation of the same, and

Figure 5 is an elevation of the sliding catch.

Referring to the drawings, each end of the bracelet *a* terminates in a flat plate, one *a*¹ of which constitutes the slotted striking-plate already referred to, whilst to the other

*a*² are rigidly fixed a pair of hasps *b* respectively adapted to pass through correspondingly placed slots *c* in the striking-plate *a*¹; the striking-plate and hasp-plate being adapted to lie face to face when the bracelet *a* is closed as shown in Figure 1. Behind the striking-plate *a*¹ a slide *d* is fitted to reciprocate in guides which extend transversely of the bracelet and are formed by bending the plate *a*¹ back upon itself as shown in Figure 1. The slide *d* is pressed towards one edge of the bracelet by a coiled spring *e* housed in a tube *f* fixed to the back of the striking-plate *a*¹, the spring *e* being held in compression between a projection *d*¹ on the back of the slide *d* and the inner end *f*¹ of the tube *f*. The slide *d* is gapped as at *d*² to give passage to the hasps *b*, one edge *b*¹ of each of which is bevelled from the point rearwards (see Figures 1 and 3). The gaps *d*², when the slide *d* is freed to the action of its spring, remain so far open as to afford entrance for the points of the hasps, as shown in broken lines in Figure 3. Hence when the ends of the bracelet *a* are brought together, the hasps *b* pass through the slots *c* in the striking-plate *a*¹ and through the gaps *d*² in the slide *d*, causing the slide *d* to move against the stress of its spring *e* until the striking and hasp plates *a*¹ and *a*² respectively contact with one another, whereupon the slide *d* is moved in the opposite direction by the spring *e*, so as to cause the ends of the gaps *d*² to enter notches *b*² formed in the respective hasps at the rear of their bevelled edges.

The slide *d*, consisting of a flat strip of metal, is formed with an extension which projects beyond that edge of the bracelet *a* towards which the slide *d* is pressed by its spring *e*, this extension being headed as at *d*³ to constitute a plunger by means of which the slide *d* can be forced back, by a touch of the finger, to release the slide from the hasps when it is desired to unfasten the bracelet. A notch *d*⁴ is formed in the outer edge of the slide-extension or plunger, immediately outside of the edge of the bracelet, to receive a tumbler-lever *g* so pivoted at *g*¹ to the corresponding edge of the hasp-end of the bracelet as to swing in a plane parallel to the same edge of the bracelet; the tumbler-lever *g* being adapted, by its engagement with said notch, *d*⁴, to prevent

the actuation of plunger d^3 to release the slide d from the notches b^2 in the hasps b . The free end of the tumbler-lever is preferably hooked to engage over the farther 5 side of the plunger (see Figures 2 and 4,) so as to co-operate with the hasp-fastening in holding the ends of the bracelet together. The tumbler-lever g may be provided with a small operating knob g^2 .

10 More particularly in cases where the scale of the parts is sufficiently large, the notches b^2 in the hasps may be so tapered that movement of the slide under the stress of its spring will tend to draw the striking and 15 hasp plates more closely together. Similarly, the notch d^4 in the plunger may be so tapered that the forcing of the tumbler-lever g into said notch will tend to draw the operative extremities of the slide gaps 20 d^2 into deeper engagement with the notches b^2 in the hasps. Moreover, the hook on the free end of the tumbler-lever g may likewise be tapered so as to tend to become wedged against the farther side of the 25 plunger when engaged therewith.

I claim:—

1. A fastening device for bracelets, necklaces and other articles of jewelry comprising inter-connecting parts on the contiguous 30 faces of the two members, a sliding catch adapted to engage the inter-connecting parts to lock the same, a plunger associated with said sliding catch and adapted when actuated to unlock the said parts and means 35 adapted to engage the plunger so as to prevent accidental actuation thereof.

2. A fastening for bracelets, necklaces and other articles of jewelry comprising a slotted striking plate on one member, a sliding 40 catch carried by said striking plate, a spring operative on said sliding catch to tend to move it in a direction to close the slots in said striking plate, hasps on the other member adapted to pass through the slots in the 45 striking plate, said hasps having detents adapted for interlocking engagement with the sliding catch to prevent mutual separation of the members when in the locked position, a plunger associated with the sliding 50 catch and adapted to be moved in the direction to open the slots and release the hasps and means adapted to engage the plunger so as to prevent accidental actuation thereof.

3. A fastening for bracelets, necklaces and 55 other articles of jewelry comprising a slotted striking plate on one member, a sliding catch carried by said striking plate, and having hasp receiving slots, a spring operative on said sliding catch to tend to move 60 it in a direction to close the slots in said striking plate, hasps on the other member adapted to pass through the slots in the striking plate, said hasps having cam surfaces on their ends to engage and move the 65 sliding catch in the direction to open the

slots during the passage therethrough of the hasps, said hasps having detents adapted for interlocking engagement with the sliding catch to prevent mutual separation of the members when in the locked position, a 70 plunger associated with the sliding catch and movable in the direction to open the slots and release the hasps and means adapted to engage the plunger so as to prevent accidental actuation thereof. 75

4. A fastening for bracelets, necklaces and other articles of jewelry comprising a slotted striking plate on one member, a sliding catch carried by said striking plate, a spring operative on said sliding catch to 80 tend to move it in a direction to close the slots in said striking plate, hasps on the other member adapted to pass through the slots in the striking plate, said hasps having detents adapted for interlocking engagement with the sliding catch to prevent mutual separation of the members when in the locked position, a plunger associated with the sliding catch for moving said catch in the direction to open the slots and release 85 the hasps and a tumbler lever pivoted to the member which carries the hasps to engage the said plunger to prevent accidental actuation thereof.

5. A fastening for bracelets, necklaces and other articles of jewelry comprising a slotted striking plate on one member, a sliding catch carried by said striking plate, a spring operative on said sliding catch to 90 tend to move it in a direction to close the slots in said striking plate, hasps on the other member adapted to pass through the slots in the striking plate, said hasps having cam surfaces on their ends to engage and move the sliding catch in the direction to open the slots during the passage therethrough of the hasps, said hasps also having detents adapted for interlocking engagement with the sliding catch to prevent mutual separation of the members when in 95 the locked position, a plunger associated with the sliding catch for moving said catch in the direction to open the slots and release the hasps and a tumbler lever pivoted to the member which carries the hasps to engage the said plunger to prevent accidental actuation thereof. 100

6. A fastening for bracelets, necklaces and other articles of jewelry comprising a slotted striking plate on one member, a 105 sliding catch carried by said striking plate, a spring operative on said sliding catch to tend to move it in a direction to close the slots in said striking plate, hasps on the other member adapted to pass through the slots in the striking plate, said hasps having detents adapted for interlocking engagement with the sliding catch to prevent mutual separation of the members when in 110 the locked position, a plunger associated with the sliding catch for moving said catch in the direction to open the slots and release the hasps and a tumbler lever pivoted to the member which carries the hasps to engage the said plunger to prevent accidental actuation thereof. 115

- with the sliding catch for moving said catch in the direction to open the slots and release the hasps and a curved tumbler lever pivoted to the member which carries the hasps to engage the said plunger to prevent accidental actuation thereof, the engagement of the tumbler lever with the plunger tending to draw the striking plate and hasp member together.
7. A fastening for bracelets, necklaces and other articles of jewelry comprising a slotted striking plate on one member, a sliding catch carried by said striking plate and having an abutment on its rear face, a tube carried by said striking plate, a spring between the inner end of said tube and said abutment and operative to move the sliding catch in a direction to close the slots in said striking plate, hasps on the other member adapted to pass through the slots in the striking plate, said hasps having detents adapted for inter-locking engagement with the sliding catch to prevent mutual separation of the members when in the locked position, a plunger associated with the sliding catch for moving said catch in the direction to open the slots and release the hasps and a curved tumbler lever pivoted to the member which carries the hasps to engage the said plunger to prevent accidental actuation thereof, the engagement of the tumbler lever with the plunger tending to draw the striking plate and hasp member together.
8. A fastening for bracelets, necklaces and other articles of jewelry comprising a slotted striking plate on one member, a sliding catch carried by said striking plate, said sliding catch having an abutment on its rear face, a tube carried by said striking plate, a spring arranged between the inner end of said tube and said abutment to move the sliding catch in a direction to close the slots in said striking plate, hasps on the other member adapted to pass through the slots in the striking plate, said hasps having detents adapted for inter-locking engagement with the sliding catch to prevent mutual separation of the members when in the locked position, a plunger associated with the sliding catch for moving said catch in the direction to open the slots and release the hasps and a curved tumbler lever pivoted to the member which carries the hasps to engage the said plunger to prevent accidental actuation thereof, the engagement of the tumbler lever with the plunger tending to draw the striking plate and hasp member together.

In testimony whereof I have signed my name to this specification.

ANDREW DOWNES.
